Inventor
Thaddeus Davids

Das. 1078

Thaddeus Davids, of New York, N. Y.
Letters Patent No. 1678, Dated Jan'y 11. 1859.

The schedule referred to in these Letters Patent and making part of the same.

To all whom it may concern:

Be it known that I, Thaddeus Davids, of the City, County and State of New York, have invented or produced a new and original Design for an Ink Bottle, and I do hereby declare that the following is a full, clear and exact description of the same, reference being had to the annexed drawings making a part of this Specification, in which

Fig: 1. is a plan or top view of an ink bottle constructed or formed according to my design.

Fig: 2. an elevation of do.

Similar letters of reference indicate corresponding parts in the two figures.

This invention consists in having the lower portion of the bottle of conical or "petticoat" form, and the upper portion at its junction with the lower portion made to project over the lower portion, and form a bead, the upper portion gradually decreasing in diameter to the neck, and forming a concave external surface, the neck of the bottle at its junction with the body having a bead or ring around it, and the mouth provided with a spout or nozzle, the whole forming a chaste and neat design for the purpose intended.

A. represents the lower portion of the bottle, which is a frustum of a cone, and B, is the upper portion, which at its junction with the part A, projects over it, and forms the bead a, as shown plainly in fig: 2.

The upper portion B, gradually decreases in diameter from its lower to its upper end, and in such a manner as to form a concave external surface, b, see fig: 2.

C. is the neck of the bottle, which has a ring or bead c. around it at its junction with the part B. of the bottle. The neck C, is of concave form, at first decreasing in diameter

Des. 1078

from the ring or bead c. and then gradually expanding to the mouth of the bottle, the mouth being provided with a nozzle or Spout d.

Having thus described my invention what I claim as new and desire to secure by Letters Patent, is,

The general configuration of the parts as herein shown and described to form a new and original design for an ink bottle.
